HYDRAULICALLY OPERATED GRINDING
MACHINEWallace H. Wood, Worcester, Mass., assignor to
Norton Company, Worcester, Mass., a corpora-
tion of Massachusetts

Application April 1, 1936, Serial No. 72,115

7 Claims. (Cl. 51—95)

This invention relates to grinding machines, and more particularly to a hydraulically operated cylindrical grinding machine.

One object of this invention is to provide a simple and thoroughly practical hydraulically driven cylindrical grinding machine. A further object of this invention is to provide an improved hydraulically operated table reciprocating mechanism for the reciprocable table of a cylindrical grinding machine.

A further object of this invention is to provide a simplified valve control unit which serves not only to control the table movement but also the wheel feeding movement. A further object is to provide a readily controllable dwell control mechanism for controlling the extent of dwell at each end of the table reciprocation. Other objects will be in part obvious or in part pointed out hereinafter.

20 This invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of the improved grinding machine, having parts broken away and shown in section to more clearly show the construction;

Fig. 2 is a diagrammatic view, showing the valve and piping diagram of the hydraulic table reciprocating and wheel feeding mechanism;

Fig. 3 is a fragmentary vertical cross sectional view, on an enlarged scale, taken approximately on the line 3—3 of Fig. 1;

Fig. 4 is a fragmentary vertical section, taken approximately on the line 4—4 of Fig. 3;

Fig. 5 is a fragmentary detail view of the control for the reverse and traverse valves, on an enlarged scale, taken approximately on the line 5—5 of Fig. 3; and

Fig. 6 is a fragmentary vertical section, on an enlarged scale, taken approximately on the line 6—6 of Fig. 3, showing the connection between the reversing and wheel feed control valve.

A grinding machine has been illustrated in the drawings comprising a base 10 which supports a transversely movable wheel slide 11 thereon. The wheel slide 11 is mounted for a transverse movement on a V-way (not shown) and flat way in a manner similar to that shown in the expired patent to Norton No. 762,838 dated

June 14, 1904. The wheel slide 11 supports a rotatable grinding wheel 12 on a rotatable wheel spindle 13. The wheel spindle 13 may be rotated by means of an electric motor 14 mounted on the upper surface of the wheel slide. The motor is provided with a rotor shaft 15 which is provided with a pulley 16 connected by a belt 17 with a pulley 18 mounted on the wheel spindle 13.

The base 10 also supports a longitudinally reciprocable work table 25 on V-way and flat way 19, as indicated in the above-mentioned expired prior patent to Norton. The table 25 serves to rotatably support a cylindrical work piece 26 on a headstock 27 and a footstock 28. The headstock 27 is provided with a headstock center 29 and the footstock 28 is provided with a footstock center 30 which are arranged to engage center holes in the opposite ends of a work piece to rotatably support the same during a grinding operation. The headstock 27 is provided with a rotatable face plate 31 which may be driven from any suitable source of power, such as a motor on the headstock or an overhead belt drive. The plate 31 carries a driving pin 32 which engages a dog 33 mounted on the end of the work piece 26 to rotate the work piece for a grinding operation.

Wheel feed

The wheel slide 11 may be fed transversely relative to the base 10 by means of a half nut (not shown) and a rotatable feed screw 35 which is rotatably supported in bearings (not shown) in the base 10. These parts have not been shown in detail, since they are not considered part of the present invention. For further details of construction of this nut and screw mechanism, reference may be had to the above-mentioned prior patent to Norton No. 762,838. The outer end of the feed screw 35 carries a gear 36 meshing with a small gear 37 rotatably mounted on a shaft 38. A feed wheel 39 is also rotatably supported on the shaft 38 and is either formed integral with the gear 37 or rigidly fastened thereto so that when the hand wheel 39 is rotated, a rotary motion will be transmitted through the gear 37, the gear 36, to rotate the feed screw 35 so as to cause a transverse feeding movement of the slide 11 and grinding wheel 12 either toward or from the work piece 26, depending on the direction of rotation of the feed wheel 39. The feed wheel 39 may be rotated manually, if desired. A micrometer adjusting mechanism 40 is provided on the hand wheel 39 and carries an abutment 41 which is arranged in the path of a feed pawl 42 which is pivotally mounted on

a stud 43. The micrometer adjusting device 40 facilitates the resetting of the stop abutment 41 relative to the feed wheel 39 to make compensation for wheel wear to accurately size the work piece. The feed pawl 42 is preferably arranged for a reciprocatory motion to engage the teeth of the feed wheel 39 so as to cause an automatic infeeding movement of the grinding wheel when desired. The movement of the feed pawl 42 is preferably accomplished by means of a fluid pressure mechanism including a cylinder 44 which contains a slidably mounted piston 45. A piston rod 46 is formed integral with the piston 45 and carries at its upper end a bracket 47 which serves as a support for the stud 43. It is desirable to provide a suitable means for adjusting the extent of movement of the feed pawl 42. This may comprise an adjustable stop screw 48 which is carried by a projecting lug 49 on the base 10. The stop screw 48 is arranged in the path of a projecting portion of the bracket 47 carried by the piston 45 so that the upward movement of the piston 45 together with the upward movement of the pawl 42 may be varied as desired so that one or more teeth of the feed wheel 39 may be picked up at each reciprocation of the feed pawl 42.

Table reciprocation

The longitudinally movable work table 25 is slidably mounted on V and flat ways (not shown) and is arranged to be automatically reciprocated longitudinally relative to the base 10 so as to reciprocate the work piece 20 in operative relation with the grinding wheel 12. The reciprocating mechanism preferably comprises a hydraulic system including a cylinder 55 which is fixed to the under side of the table 25. The cylinder 55 contains a pair of spaced pistons 56 and 57 which are connected by hollow piston rods 58 and 59 respectively with supporting brackets 60 and 61 respectively which are rigidly mounted on opposite ends of the base 10. A fluid pressure reversing valve 65 is provided to control the admission of fluid under pressure to cylinder chambers 62 and 63 respectively, at opposite ends of the cylinder 55. The reversing valve 65 is preferably of a piston type in which a plurality of valve pistons 66, 67, 68 and 69 are formed integral with the valve stem 65.

Fluid under pressure is supplied by means of a pump 75 which is preferably located within the base 10. The pump 75 draws fluid through a pipe 76 from a reservoir or sump 77 which is also located within the base 10 and forces fluid through a pipe 78, a passage 79 within a valve casing 70, and through a passage 80 into a valve chamber 81 located between the valve pistons 66 and 67 and through a passage 82 into a valve chamber 83 located between the valve pistons 68 and 69. In the position of the parts, as illustrated in Fig. 2, fluid under pressure entering the valve chamber 81 passes out through a passage 84, through a pipe 85, and through a central aperture 86 within the piston rod 58 and into the cylinder chamber 62 to cause the cylinder 55 and the table 25 to move toward the left, as viewed in Fig. 2. During the admission of fluid under pressure to the cylinder chamber 62, fluid is exhausted from the cylinder chamber 63 through a central aperture 88 within the piston rod 59, through a pipe 89, a passage 90 within the valve casing 70, into a valve chamber 91, and exhausts therefrom through a passage 92. In order to automatically control the move-

ment of the reversing valve 65, a pilot valve 99 is provided which is automatically actuated in timed relationship with the table movement to cause a reversal in the direction of movement of fluid under pressure. As illustrated in Fig. 2, the pilot valve is preferably of a piston type comprising a valve stem 100 having formed integral therewith valve pistons 101, 102, 103 and 104. The fluid under pressure from the pump 75 and pipe 78 passes through a passage 105 into a valve chamber 106 formed between the valve pistons 102 and 103. When the pilot valve is shifted toward the right (Fig. 2), fluid under pressure entering the valve chamber 106 passes outwardly through a passage 107 into a valve chamber 108 in the reversing valve 65 formed between the valve piston 69 and the end of the valve casing. Fluid under pressure entering the chamber 108 serves to move the reversing valve toward the left (Fig. 2). This movement of the reverse valve 65 toward the left causes valve piston 67 to close the passage 84 and after a further movement of the valve, shifts the valve piston 68 so that fluid under pressure from the passage 82 into valve chamber 83 passes through passage 90 and pipe 89 into the cylinder chamber 63 to cause the cylinder 55 and table 25 to start moving toward the right, as viewed in Fig. 2.

In grinding a cylindrical work piece, it is desirable to provide a dwell at the end of the reciprocatory stroke in order that the work piece may make at least one complete rotation while the grinding wheel is at the end of its reciprocatory stroke in order that the grinding wheel may grind completely around the work piece to grind the same to a true cylinder before the work piece starts moving in the reverse direction. The extent of dwell is preferably regulated by a needle valve 110 in the passage 107 which serves to regulate the fluid passing through the passage 107 and thereby regulates the speed of shifting of the reverse valve 65.

Similarly, when the pilot valve stem 100 is moved toward the left, as viewed in Fig. 2, fluid under pressure entering the chamber 106 passes outwardly through a passage 112 into a valve chamber 113 which is formed between the valve piston 66 and the end of the valve casing. Admission of fluid under pressure to the chamber 113 serves to move the reversing valve 65 toward the right, into the position illustrated in Fig. 2, so as to reverse the direction of flow of fluid within the system. A needle valve 114 is provided in the passage 112 and serves to regulate the passage of fluid under pressure through the passage 112 and consequently regulates the speed of movement of the reverse valve 65 toward the right so as to control the extent of dwell when the table is at the end of its reciprocatory stroke. By adjusting the needle valves 110 and 114, the extent of dwell at each end of the table stroke may be varied, as desired.

When the pilot valve 99 is in the position as illustrated in Fig. 2, fluid within the valve chamber 108 may exhaust through passage 107, passage 116, into valve chamber 117, and through a passage 118, into a valve chamber 119, and out through a passage 120 and an exhaust pipe 121 into the reservoir 77.

Similarly, fluid within the valve chamber 113 may exhaust through the passage 112, a passage 123, into a valve chamber 124, through a passage 125, into a valve chamber 126, and out through 75

a passage 127 and the pipe 121 into the reservoir 77.

The pilot valve 99 is normally maintained in a central position, as indicated in Fig. 2. A yieldable device including a pair of opposed springs is utilized to maintain the pilot valve in its neutral or central position. A bell crank lever 130 is rotatably mounted on a stud 131 which is fixedly mounted relative to the base 10. The bell crank 130 has an upwardly extending arm 132 which is connected by means of a stud 133 and a roller 134 with a groove 135 in an end block 136 which is fixedly mounted on the end of the valve stem 100. In the preferred construction, the stud 131 together with the valve actuating mechanism is supported in an apron 137 which is fixedly mounted on the base 10. The forward end of the bell crank member 130 is provided with outwardly extending arms 138 and 139 which extend at substantially right angles to the arm 132. The arms 138 and 139 carry adjustable stop screws 140 and 141 respectively which bear against the lower ends of a pair of vertically arranged slideable rods 142 and 143. The rods 142 and 143 are slidably supported in the apron 137. The bell crank 130 and the valve 99 are held in a central position, as indicated in the drawings, by means of a pair of springs 145 and 146 which surround reduced end portions 147 and 148 of the rods 142 and 143 respectively. Collars 149 and 150 are fixedly mounted on the lower ends of the portions 147 and 148 of the rods 142 and 143, and the springs 145 and 146 are interposed between the fixed collars 149 and 150 and a pair of slidably mounted collars 151 and 152 which are located on the portions 147 and 148 of the rods 142 and 143 respectively. By adjusting the screws 140 and 141, the tension of the springs 145 and 146 may be adjusted or balanced to normally hold the bell crank 130 and the valve 99 in the central or neutral position as indicated in Fig. 2.

In order to automatically actuate the pilot valve 99 in timed relation with the table movement, a pair of adjustable dogs 155 and 156 are adjustably supported in a T-slot 157 formed in the front edge of the table 25. The dogs 155 and 156 are preferably staggered (Fig. 3), that is one of the dogs projects forward to a greater extent than the other. The dog 155 is arranged in the path of a roller 158, and the dog 156 is arranged in the path of a roller 159 so that when the dog 155 or 156 engage either the roller 158 or 159, the dogs will transmit a downward movement to one of the rollers 158 or 159 which serves through rods 142 or 143 to rock the bell crank 130 and thereby shift the pilot valve stem 100 from a central position, as indicated in Fig. 2.

The rollers 158 and 159 are rotatably supported on the upper ends of vertically extending plungers 160 and 161 respectively. These plungers 160 and 161 are slidably mounted within sleeves 162 and 163 respectively. The sleeves 162 and 163 are preferably removably mounted within the apron 137 so as to facilitate adjustment of the mechanism. In order to prevent the plungers 160 and 161 from turning within their respective sleeves 162 and 163 and the apron 137, and in order to maintain the rollers 158 and 159 always in operating position with respect to the dogs 155 and 156, each of the plungers 160 and 161 is provided with a keyway 164 and 165 respectively. A screw 167 is mounted in the apron 137 and has a projecting end portion which passes through a hole in the sleeves 162 and 163 and engages the keyways 164 and 165 in the plungers 160 and 161

respectively. Only one of the screws 167 has been illustrated in Fig. 3 as passing through the sleeve 163 and engaging the keyway 165. A similar screw passes through the apron 137 and through sleeve 162 and engages the keyway 164 to hold the plunger 160 against rotation. The plungers 160 and 161 are provided at their lower ends with adjustable stop screws 168 and 169 respectively which are screw threaded into the ends of the plungers and are held in adjusted position relative thereto by means of lock nuts 170 and 171. The heads of the screws 168 and 169 bear against the upper end surfaces of the rods 142 and 143 respectively. The plungers 160 and 161 may be readily removed from the apron 137 by removing the screws 167 and withdrawing the plunger 160 and 161 together with its supporting sleeve 162 and 163 vertically from the apron. The adjusting screws 168 and 169 may then be readily adjusted so that when the plungers 160 and 161 are assembled in the machine, the rollers 158 and 159 will project vertically to the desired extent with relation to the dogs 155 and 156 respectively.

When the table 25 is moved longitudinally, as shown in the drawings, the longitudinal movement continues until the dog 155 or 156 engages the roller 158 or 159 respectively and the dog serves to move the roller and plunger downwardly so as to rock the bell crank 130 against the tension of the spring 145 or 146 to move the pilot valve stem 100 from a central position and to admit fluid under pressure to either the end chamber 108 or the end chamber 113 in the reversing valve 65 so that the valve is thereafter shifted into a reverse position by fluid under pressure.

It is desirable that the reversing valve 65 be moved quickly when the table reaches the end of its stroke so as to stop the table movement. This is preferably accomplished by providing an interconnection between the pilot valve 99 and the reversing valve 65 so that during the initial movement of the pilot valve by means of the dogs 155 and 156 and rollers 158 and 159, the reversing valve will be positively shifted to cut off the exhaust of fluid from the system so as to stop the table movement. This is preferably accomplished by means of a rock arm 175 which is pivotally mounted on a stud 176. One end of the rock arm 175 is connected by a stud 177 with a groove 178 in the head 136 fixedly mounted on the end of the valve stem 100. The other end of the rock arm 175 is provided with a stud 179 which is arranged to engage either the collar 180 or a collar 181 which are mounted on the end of the reverse valve stem 65. As indicated in Figs. 2, 5 and 6, the stud 179 is in engagement with the collar 180. When the table reaches the end of its stroke, that is so that the dog 156 moves the roller 159 downwardly to rock the bell crank 130 in a clockwise direction (Fig. 4), it serves to shift the pilot valve stem 100 toward the right (Fig. 2). This movement also serves through the rock arm 175 to move the stud 179 in a counterclockwise direction (Fig. 2) toward the left so as to shift the valve 65 toward the left (Fig. 2) and thereby cause the valve piston 68 to cover the passage 90 to stop the table movement. This movement of the reverse valve is caused directly by the adjustable dog 156 on the table and roller 159 through the bell crank 130 and rock arm 175. The movement of the valve stem 100 toward the right (Fig. 2) serves to move the valve piston 103 so as to uncover the passage 107 and admit fluid under pressure into the valve chamber 108 to complete the movement of the reversing valve by the controlled influence

of fluid under pressure. By regulating the admission of fluid under pressure into the chamber 108, the extent of dwell of the table at the end of its stroke may be varied, as desired.

5 Similarly, when the reverse valve 65 is at the other end of the table stroke, the stud 179 engages the collar 181 mounted on the end of the valve stem 65, so that when the dog 155 engages the roller 158 and rocks the bell crank 130 in a 10 counterclockwise direction to shift the pilot valve toward the left (Fig. 2), this movement serves through rock arm 175 and stud 179 to move the collar 181 toward the right (Fig. 2) to again shift the reverse valve 65 to cut off the exhaust of fluid 15 from the system and admit fluid under pressure from the valve chamber 106, through the passage 112, the needle valve 114, into the reverse valve chamber 113, to again shift the reversing valve into the position illustrated in Fig. 2.

20 The reversal of the table movement may be readily controlled by varying the shape of the cam surface formed on the lower operative faces of the adjustable table dogs 155 and 156. By varying the shape of the dog faces, the pilot valve and 25 the reversing valve may be moved at a controlled rate to cut off the supply of fluid and stop the table movement in one direction before the valve is shifted into a reverse direction, as controlled by the pilot valve. Thus, either an abrupt stopping 30 of the table movement or a gradual slowing down may be obtained, as desired.

It is desirable to provide a manual control for the reversing mechanism so that the table 25 may be manually reversed in its direction of movement when desired. In the preferred construction, a manually operable control is provided to shift the reversing valve 65. A manually operable control lever 185 is mounted on the outer end of a rock shaft 186, which is rotatably supported in 40 a portion of the apron 131. The inner end of the rock shaft 186 is provided with a downwardly extending arm 187 having a stud 188 engaging a groove 189 in a connecting member 190 which is fixedly mounted on the valve stem 65 between 45 the collars 180 and 181. By shifting the lever 185 either toward the right or toward the left, the reversing valve 65 may be readily shifted to change the direction of movement of the table 25 under the influence of fluid pressure.

50 A suitable speed controlling mechanism is provided for the table movement so that the speed of reciprocation of the table may be readily adjusted to a desired speed for grinding. This is preferably accomplished by means of a control valve 190. This valve is preferably of a piston type and is preferably arranged to control the exhaust of fluid from the system. As illustrated in Fig. 2 of the drawings, fluid under pressure exhausting from the cylinder chamber 63 through 55 the passage 88 in the connecting rod 59, through the pipe 89, the passage 90, and valve chamber 91, passes outwardly through a passage 92 and a port 191 into a valve chamber 192 and through a pipe 193 which exhausts into the reservoir 17. 60 The control valve 190 preferably comprises a pair of spaced pistons 194 and 195 which are preferably formed integral with a valve stem 197. The end 196 of the piston 195 is slabbed off at an angle relative to the axis of rotation of the piston 195, the end 196 being 70 ton and is arranged to throttle the fluid passing through the port 191 when the valve 190 is moved toward the left (Fig. 2). By rotating the valve piston 195, the aperture of the port 191 may be varied so that the speed of the table may be 75 varied from a maximum to a minimum speed.

The valve stem 197 carries at its outer end an adjusting knob 198 which is provided with a dial 199 cooperating with an index finger 200 to locate the valve in the desired rotary position for producing the required table speed. The index finger 200 is carried by a sleeve 201 which fits on the valve stem 197 and is held against rotation by means of a manually operable control lever 202. The control lever 202 is pivotally mounted on a stud 203 carried by a bracket 204 fixed to the base of the machine. In the full line position of the valve 190 and the control lever 202, as shown in Fig. 2, the table 25 is reciprocating at a maximum speed. By rotating the valve control knob 198, the slabbed-off portion may 15 be turned to close a portion of the port 191 to slow down the table movement. When it is desired to stop the table movement, the valve control lever 202 is moved from the full line position into the dotted line position 202a (Fig. 2) 20 so that the valve piston 195 closes the port 191, thereby stopping the exhaust of fluid from the chamber 63 and stopping the movement of the table 25. At the same time, a valve chamber 205 located between the valve pistons 194 and 195 25 is moved into the dotted line position (Fig. 2) which serves to connect a passage 206 with a pipe 207 so that fluid may by-pass from the cylinder chamber 62 into the cylinder chamber 63 30 when the table is traversed manually by mechanism to be hereinafter described. The fluid may by-pass from the cylinder chamber 62 through the passage 86 in the piston rod 58, through a pipe 85, through the passage 206, valve chamber 205, and pipe 207, into pipe 89, through the passage 88 within the piston rod 59 and into the cylinder chamber 63, thus forming a free passage 35 of fluid between the opposite ends of the cylinder.

In the dotted line position 202a of the control lever 202, the table 25 may be traversed longitudinally by a manually operable traverse mechanism without the necessity of overcoming the fluid pressure within the system due to the by-pass of fluid above described. A manually operable traverse mechanism has been illustrated 45 comprising a rack bar 210 depending from the under surface of the table 25. A gear 211 which is rotatably mounted on a shaft 212 meshes with the rack bar 210. The shaft 212 also carries a large gear 213 which is either integral with or 50 fixed to the gear 211. The gear 213 meshes with a small gear 214 rotatably supported on a shaft 215 and fixed to a hand wheel 216. By rotating the hand wheel 216 in either direction, a rotary motion is transmitted through the gear 214, 213 55 and 211 to move the rack bar 210 endwise and to impart a corresponding traversing movement to the table 25.

The wheel feeding mechanism above described is preferably interconnected with the fluid pressure table reciprocating mechanism so that the infeeding movement of the grinding wheel takes place at the end of a reciprocatory stroke of the table. As illustrated in Fig. 2, fluid under pressure from the pipe 78 passes through a pipe 217 60 into a cylinder chamber 218 above the piston 45. The cross sectional area of the piston rod 46 is relatively large compared with the cross sectional area of the piston 45, thereby producing a differential effective area on the upper and lower surfaces of the piston 45. The effective area of the lower surface of the piston 45 is greater than the effective area of the upper surface thereof and serves to cause an upward movement 70 of the piston 45 when fluid under pressure from 75

the same source is admitted to a lower cylinder chamber 219. The piston 45 is normally held in a down position by the continuous supply of fluid pressure entering the cylinder chamber 218.

5 In order to produce a controlled infeeding movement, a feed control valve is provided for controlling the admission of fluid to the cylinder chamber 219. A wheel feed control valve 220 of the balanced piston type is provided comprising 10 a valve stem 221 having formed integrally therewith valve pistons 222, 223, 224 and 225. In order that the infeed of the grinding wheel 12 may take place during the period of reversal, it is desirable that the control valve 220 be operated in timed 15 relation with the reversing valve 65. As illustrated in the drawings, this is preferably accomplished by connecting the valve stem 221 with the valve stem 65, preferably by means of a link 226 which is rigidly fixed to the stems of each of said 20 valves so that when the reversing valve 65 is shifted to reverse the direction of movement of the table 25, fluid under pressure from the passage 105 passes downwardly through a passage 227 which, as shown in Fig. 2, is blocked by the 25 valve piston 223. When the reverse valve 65 starts moving toward the left (Fig. 2), the valve stem 221 is also moved toward the left by means of the link 226. After the valve stem moves toward the left a sufficient distance to uncover 30 the passage 227, fluid under pressure may pass for an instant through a valve chamber 228 and out through a pipe 229 into the valve chamber 219, thereby causing a differential pressure which is greater on the under surface of the piston and 35 serves to move the piston upwardly, carrying the feed pawl 42 to move it idly over the feed wheel 39. The passage of fluid to the chamber 219 is permitted only for an instant, after which the valve piston 224 closes the port admitting fluid 40 to the pipe 229, and fluid under pressure within the pipe 229 and cylinder chamber 219 may then exhaust through a valve chamber 119 and out through a passage 120 and pipe 121 into the reservoir 77.

45 On the reverse movement of the valve stem 221, fluid under pressure is admitted instantaneously through the pipe 229 to cause an infeeding movement of the wheel at the other end of the table stroke. When the valve piston 224 cuts off the flow of fluid through the pipe 229 and allows the fluid within the cylinder chamber 219 and pipe 229 to exhaust through the valve chamber 126 and passage 127 into the reservoir 77, the continuous fluid under pressure applied through 55 the pipe 217 causes the piston 45 to again move downwardly, causing the feed wheel 39 to rotate in a counterclockwise direction to cause an infeeding movement of the grinding wheel 12.

The operation of the machine is readily apparent from the foregoing disclosure. A work piece 60 26 is mounted on centers 29 and 30 and the work and wheel are started in rotation. The table dogs 155 and 156 are then located along the front edge of the table 25 within the T-slot 151 so that the 65 table may be reciprocated to pass the desired portion of the work piece 26 across the operative face of the grinding wheel 12. The knob 198 is then rotated to the desired table speed and the control lever 202 is moved from the dotted line 70 position 202a (Fig. 2) into the full line position to start the table reciprocation. The adjustable stop screw 48 may then be adjusted so that the desired movement of the feed pawl 42 may be obtained to cause either one or more teeth on 75 the feed wheel to be picked up at each recipro-

cation of the feed pawl. The speed of movement of the feed pawl in an upward direction may be readily adjusted by means of an adjustable valve 231 which is located between the pipe 229 and the cylinder chamber 219. Similarly, the admission of continuous fluid under pressure to the cylinder chamber 218 may be controlled by a valve 232 so that the speed of movement of the feed pawl 42 in either direction may be independently adjusted, as desired. The needle valve 110 and 10 114 may then be adjusted to vary the extent of dwell at each end of the table reciprocation in order that the work piece may rotate at least one complete turn at the end of the table stroke before the table starts its movement in the reverse 15 direction.

It will thus be seen that there has been provided by this invention apparatus in which the various objects hereinabove set forth together with many thoroughly practical advantages are 20 successfully achieved. As many possible embodiments may be made of the above invention and as many changes might be made in the embodiment above set forth, it is to be understood that all matter hereinbefore set forth or shown in the 25 accompanying drawings is to be interpreted as illustrative and not in a limiting sense.

I claim:

1. A grinding machine comprising a transversely movable rotatable grinding wheel, means 30 including a piston and cylinder to feed said wheel transversely, a longitudinally movable work supporting table, means including a piston and cylinder to reciprocate said table, a fluid pressure system including a pump, a reversing valve to 35 change the direction of fluid pressure to said cylinder, a pilot valve to control the movement of said reverse valve, a bell crank lever operatively connected to said pilot valve, a pair of balanced springs to hold said lever and valve in a neutral 40 or central position, a pair of movable plungers carried by said base which are operatively connected to actuate said lever and valve, adjustable staggered dogs on said table, and a roller on each of said plungers, each of which is arranged in 45 the path of one of said dogs.

2. A grinding machine comprising a transversely movable rotatable grinding wheel, means including a piston and cylinder to feed said wheel transversely, a longitudinally movable 50 work supporting table, a fluid pressure system which is arranged to reciprocate said table including a pair of adjustable staggered dogs on said table, a pair of plungers carried by said base each of which is arranged in the path of 55 one of said dogs, a pilot valve which is normally held in a central or neutral position and which is actuated in either direction by one of said plungers, a reversing valve which is operatively connected to reverse the direction of fluid in 60 said table cylinder, and connections between said pilot valve and reverse valve whereby movement of either of said plungers serves to move the reverse valve to stop the table movement and fluid from the pilot valve serves to complete the 65 movement of the reverse valve to start the table moving in the reverse direction.

3. A grinding machine table reciprocating mechanism comprising a longitudinally movable table, a piston and cylinder operatively connected 70 to reciprocate said table, a reversing valve arranged to control the admission of fluid to said cylinder to reverse the direction of movement of said table, a control valve which serves to throttle the exhaust of fluid from said cylinder, 75

a pair of adjustable offset dogs carried by said table, a vertically movable plunger associated with each of said dogs, a pilot valve actuated by said plunger, lost motion connections between 5 the pilot valve and the reverse valve whereby the initial movement of the pilot valve serves to positively shift the reverse valve through a sufficient distance to cut off the exhaust of fluid from said cylinder, and controlled means inter- 10 posed between the pilot valve to convey controlled fluid under pressure to complete the shifting of the reverse valve.

4. A grinding machine comprising a rotatable grinding wheel, a transversely movable slide to 15 support said wheel, a pawl and ratchet feed mechanism therefor, means including a piston and cylinder to actuate said pawl and ratchet, a control valve therefor, a longitudinally reciprocable table, means including a piston and cylinder to reciprocate said table, a pair of adjustable offset dogs on said table, a pair of vertically arranged plungers each of which is aligned 20 with one of said dogs, and means including a control valve mechanism actuated by said plungers to control the reciprocation of said table and the infeed of the grinding wheel.

5. A grinding machine comprising a rotatable grinding wheel, a transversely movable slide to 30 support said wheel, a pawl and ratchet feed mechanism therefor, means including a piston and cylinder to actuate said pawl and ratchet, a control valve therefor, a longitudinally reciprocable table, means including a piston and cylinder to reciprocate said table, a pair of adjustable offset dogs on said table, a pair of vertically arranged plungers each of which is aligned 35 with one of said dogs, means including a control valve mechanism actuated by said plungers to control the reciprocation of said table and the infeed of the grinding wheel, and connections between said table control valve and said feed control valve whereby the feed control valve is 40 operated by and in timed relation with the table

control valve to cause an infeeding movement of the grinding wheel during the period of reversal.

6. In a grinding machine, a longitudinally movable table, a piston and cylinder operatively connected to reciprocate said table, a pair of adjustable offset dogs carried by said table, a pair of plungers, a roller on the upper end of each of said plungers which is aligned with one of said dogs, a reversing valve to control the 10 admission and exhaust of fluid from said cylinder, means including a pilot valve which is actuated by said dogs and plungers to shift the reversing valve, and independent adjustable connections between each of said plungers and said 15 pilot valve whereby movement of one of said plungers serves to actuate the pilot valve in one direction to reverse the movement of the table and depression of the second plunger serves to move the pilot valve in the opposite direction to again shift the direction of movement of the table.

7. In a grinding machine, a longitudinally movable table, a piston and cylinder operatively connected to reciprocate said table, a pair of adjustable offset dogs carried by said table, a pair of slidably mounted plungers, a roller on the upper end of each plunger which is arranged in the path of one of said dogs, a reversing valve to control the admission and exhaust of fluid from said cylinder, means including a pilot valve to shift said reverse valve, means including a bell crank lever to actuate said pilot valve, and adjustable connections between each of said 30 plungers and said lever whereby engagement of one of said dogs with its respective roller serves to depress the plunger and actuate the pilot valve in one direction and engagement of the second dog with the second roller serves to depress the second plunger to actuate the pilot 35 valve in the reverse direction to control the reversal of the table movement.

WALLACE H. WOOD.
